SUBMERGED FLAME EVAPORATOR

Francis Louis Holderreed, Anaconda, and Robert E. Sullivan, Butte, Mont., assignors to The Anaconda Company, a corporation of Montana

Application December 5, 1951, Serial No. 259,981

2 Claims. (Cl. 159—16)

This invention relates to the evaporation of solutions by submerged combustion, a procedure which involves introducing hot combustion gases beneath the surface of a solution to be evaporated. The invention provides an improved slotted nozzle pipe to obtain thorough distribution of the hot combustion gases into and through the solution and to minimize the intense vibration which ordinarily accompanies the operation of submerged combustion evaporators.

Submerged combustion burners, while providing a simple means of high thermal efficiency for evaporation of liquids, have been found in practice to have troublesome vibration characteristics. Such vibration is sufficiently serious as to constitute a factor limiting the commercially practicable size of submerged combustion evaporator installations. High maintenance costs due to failure of joints as a result of vibration, and the difficulties of providing satisfactory vibration-proof mountings for permanent submerged combustion units of commercial size, have been important factors in preventing more widespread adoption of evaporators of this type in preference to more conventional and more complex types of evaporation equipment.

Another feature of submerged combustion evaporators as heretofore proposed, which has substantially limited the efficiency of such apparatus, has been the geysering and excessive agitation that accompanies introduction of combustion gases directly into the body of solution to be evaporated. As a result, hot gases escape from the solution before they have transferred the maximum practicable portion of their heat content to the solution and before they have become substantially saturated with solvent vapor driven off from the solution.

The improved submerged combustion nozzle of this invention not only reduces vibration of the apparatus during operation, but also improves its efficiency by inducing a smoother flow of gases into the solution with consequent minimization of geysering and turbulence. The new apparatus comprises a closed evaporation vessel adapted to contain the solution to be evaporated, and a combustion chamber mounted preferably, although not essentially, in a vertical position above such vessel. A cylindrical nozzle pipe, open at both ends, projects substantially vertically down into the evaporation vessel, the upper end of such nozzle pipe opening to the interior of the combustion chamber and the lower end thereof opening to the interior of the evaporation vessel at a point below the normal level of solution therein. The lower end of the nozzle pipe is formed at substantially equal intervals about its circumference with slots, preferably of substantially greater length than width, and preferably but not necessarily of rectangular configuration. These slots may also advantageously be triangular in shape with their apices at the top and their bases at the lower extremity of the nozzle pipe. Triangular slots permit escape of small bubbles of combustion gases at highest pressure through the smallest openings at the top of the slots, the size of the escaping bubbles increasing as

2

the slots widen and the pressure decreases towards the bottom of the nozzle pipe. In this way improved heat transfer between gas and liquid phases is attained.

These slots advantageously extend parallel to the axis 5 of the nozzle pipe for a substantial distance up from the lower end thereof, but they terminate below the normal level of solution in the evaporator vessel and so during operation of the apparatus are wholly submerged in the solution to be evaporated. The slots are preferably numerous enough and long enough so that substantially the entire volume of hot gases delivered through the nozzle pipe passes into the solution through the slots rather than around the lower extremity of the nozzle pipe. By the provision of such slots, vibration of the apparatus and 15 geysering of the solution are both substantially reduced.

An advantageous embodiment of the invention is described below with reference to the accompanying drawing, in which

Fig. 1 is a vertical section through a submerged combustion evaporator constructed in accordance with the invention;

Fig. 2 is a perspective on an enlarged scale of the slotted nozzle pipe employed in the apparatus of Fig. 1; and

Fig. 3 is a perspective on an enlarged scale of an advantageous form of nozzle pipe having triangular slots.

The apparatus shown in Fig. 1 comprises a cylindrical combustion chamber 5 positioned vertically above a closed evaporation vessel 6 having a conical lower portion 7 and a cylindrical upper portion 8. The interior of the combustion chamber 5 communicates with the interior of the evaporation vessel 6 through cylindrical nozzle pipe 9 which is secured by bolts 10 passing through a nozzle flange 11 at the upper end of the nozzle into the base structure of the combustion chamber 5.

The combustion chamber 5 comprises a cylindrical steel shell 12 which is open at its lower end and closed at its upper end by cap 13. The shell and cap of the chamber are completely lined with a firebrick lining 14, 40 the diameter and cross-section of the chamber inside the lining being substantially the same as the nozzle pipe 9. Thus the nozzle and the combustion chamber together define a continuous interior passage of substantially uniform diameter and cross section throughout its length, 45 said passage opening at the lower end of the nozzle 9 to the interior of the evaporator vessel 6.

A mixture of gaseous fuel and air is supplied to the interior of the combustion chamber 5, wherein it is burned, through a fuel inlet pipe 15. The fuel-air mixture is prepared in a mixing chamber 16 to which an air supply pipe 17 and a fuel supply pipe 18 are connected and from which the fuel inlet pipe 15 extends. Ports 19 are provided for inspection of the interior of the combustion chamber, and for the insertion of electrical ignition points to ignite the fuel-air mixture whenever such is required.

The evaporation vessel 6 is supported by columns 20. The lower conical apex 21 of the bottom portion 7 of this vessel is connected to a feed pipe 22 through which solution to be evaporated is delivered into the vessel. An overflow pipe 23 provides for withdrawing concentrated solution from the upper portion 8 of the vessel; and a stack 24 connecting with the upper portion of the vessel provides for the escape of combustion gases and vapors from the vessel.

65 The nozzle pipe 9 extends about two-thirds, more or less, of the way down into the interior of the vessel 6, and its lower end portion 25 is formed with a group of slots 26. Fig. 2 shows the slotted lower portion of the nozzle pipe on an enlarged scale. The slots 26 are formed at substantially equally spaced intervals around the circumference of the nozzle, and extend up from the lower

end of the nozzle pipe for a substantial distance. As shown in the drawings, the slots are of rectangular configuration, and of substantially greater length than width. They are of about the same width as the metal fingers 27 which are left between them, and are disposed essentially parallel to the axis of the nozzle pipe. The nozzle pipe extends far enough into the evaporation vessel 6 so that the slots at its lower end portion are located wholly below the normal solution level 28 defined by the position of the overflow pipe 23.

Fig. 3 shows the slotted lower portion of an alternative form of the nozzle pipe 25 on an enlarged scale. The slots 28 are of triangular configuration and are formed at substantially equally spaced intervals around the circumference of the nozzle. Their apices are spaced a substantial distance up from their bases at the lower end of the nozzle pipe. The tops of the metal fingers 29 in the nozzle of Fig. 3 may with advantage be considerably wider and hence sturdier than in the case of the rectangular metal fingers in the nozzle of Fig. 2.

The use of a slotted nozzle pipe of the character just described has the effect of making the flow of hot combustion gases from the combustion chamber into the solution in the evaporation vessel much smoother than when such gases are simply discharged from the open lower end of a conventional unslotted nozzle pipe. Thereby geysering of the solution is substantially eliminated, and vibration of the apparatus very much reduced. Also, distribution of the hot gases through the solution is much improved, with a resulting improvement in the thermal efficiency of the apparatus.

In the operation of an actual evaporator installation using a nozzle having rectangular slots as shown in Fig. 2 and constructed substantially as described above for the concentration of phosphoric acid, wherein the interior of the combustion chamber 5 and nozzle pipe 9 were each some nine inches in diameter, it was found to be possible to evaporate 15 tons of water per twenty-four hours, though a rate of ten tons of water evaporated per twenty-four hours appeared best for this installation [the higher rate involved increased stack losses and undesirably high temperatures in the combustion chamber]. The installation was highly efficient; natural gas fuel was used and only about 1.5 cubic feet of fuel gas was required per pound of water evaporated.

The introduction of a considerable excess of air with the fuel gas was found to have marked advantages; it reduced the amount of vibration that occurred in the operation of the apparatus, it resulted in operation at lower temperatures, and it provided a large volume of gas to act as a carrier for the evaporated water. Optimum operation and efficiency were obtained using 40 to 50% excess of air over the amount required for complete combustion of the fuel. It was found best to provide a separate blower for the air supply and to supply air to the mixing chamber at a gauge pressure of 5 pounds per square inch.

Dilute phosphoric acid filtrate, which averaged 20% P_2O_5 content, was fed continuously to the evaporation tank at a rate which with a constant setting of air and fuel flow to the burner resulted in concentrating the acid in the evaporation vessel to a boiling temperature of about 225° F. It was found that when the temperature of the acid in the evaporation vessel was maintained constant, the product was uniform in Baumé value and grade. The typical 20% P_2O_5 filtrate was evaporated at 225° F., at 24.5 inch barometer, to 52% P_2O_5 for shipping acid. Evaporation at 210° F., at 24.5 inch barometer, gave 45% P_2O_5 for use as mixer acid in making treble superphosphate. When the installation was operated at a rate of 10 tons of water evaporated per twenty-four hours, the P_2O_5 loss was about 0.5%. Impingement devices,

scrubbers, or a Cottrell mist treater could, of course, be employed to eliminate atmospheric pollution and recover stack losses.

Some 50% of the fluorine in the dilute phosphoric acid solutions evaporated was eliminated, as compared with 30% elimination when concentrating the same solution in conventional Swenson evaporators. It was found that the quality of the concentrated product was uniformly satisfactory, particularly in that a very close control of Baumé value is possible, which is not always the case with the concentrated product from Swenson evaporators.

We claim:

1. In apparatus for the evaporation of solutions by submerged combustion comprising a closed evaporation vessel, a combustion chamber positioned above said vessel, and a cylindrical nozzle pipe open at both ends communicating at one end with said combustion chamber and at the other end extending substantially vertically downward into the evaporation vessel, the improvement which comprises forming the lower end portion of said nozzle in the evaporation vessel with a group of closely spaced slots distributed substantially uniformly about the circumference of the nozzle pipe, said slots being of triangular configuration with their bases at the lower end of the nozzle pipe and with their apices at a distance substantially greater than the width of said base up from the lower end thereof, the slotted portion of said nozzle pipe being positioned wholly below the normal level of solution in the evaporation vessel.

2. The method of concentrating solutions by evaporation which comprises combusting a mixture of fuel and air to provide hot gases of combustion, passing said hot gases of combustion admixed with an excess of about 35 from 40% to 50% of air over the amount required for complete combustion of the fuel downwardly through a body of the solution to be concentrated to a lower portion thereof, and discharging the mixture of gases of combustion and air into the solution in streams of bubbles of different size, with the bubbles of smallest size being introduced farthest from the bottom of the body of solution and with the size of the bubbles progressively increasing toward the bottom of the body of solution.
